corporation of Delaware

Application February 25, 1948, Serial No. 10,793

19 Claims. (Cl. 62—4)

1

This invention relates to a reverse cycle refrigeration system commonly referred to as a heat pump and more particularly to improvements therein relating to means for adapting the system at its optimum efficiency to different operating conditions by varying the capacity of the system.

Heretofore, heat pumps or reverse cycle refrigeration systems have been used as a heating means for buildings, water supplies and various other things requiring heat. In the reverse cycle system a refrigeration system is employed to do the heating. The difference between a reverse cycle system and an ordinary refrigeration system for cooling is that in a reverse cycle system the heat dissipated by the condenser is used for a useful purpose such as heating a room or heating water. In the ordinary refrigeration system it is the ability of the evaporator to extract heat from surrounding objects that is used for cooling some object. The evaporator of a reverse cycle system is exposed to some source of heat such as the outside air or ground or an outside source of water and the heat picked up in the refrigeration system from the outside source is discharged from the condenser and serves to heat the building or water. The discussion herein will be devoted to the application of a reverse cycle system to the heating of a building such as a home although it is to be understood that the heat made available by the reverse cycle system may be used for any desired purpose.

If a reverse cycle system is designed to heat a particular residence that system must have a capacity sufficient to heat the residence on the coldest days. It has been found that the average seasonal requirement is about 40% of the maximum requirement in a typical locality due to the fact that the most extreme heating requirements do not exist on the milder days. Heretofore, systems of fixed compressor displacement capacity have been used to heat residences throughout the season in which climatic changes produce different demands for heat. Controls have been used to regulate the time of operation of these systems but the compressor displacement capacity has remained constant. It is a principal object of this invention to provide a means for more than doubling the efficiency of such a system by unloading individual compressor cylinders to adapt the system to the heating requirements instead of running the system at full compressor displacement capacity for short intervals. This increase in efficiency is obtained by providing an automatic control of the compressor compression ratio so that the mean temperature differences

2

between the refrigerant and the heat source and the refrigerant and the substances to be heated are always at a minimum. Appreciable reductions in compression ratio are obtained thereby which greatly improve the overall efficiency during light load periods.

Some suggestions to overcome the problem presented by systems of fixed compressor displacement capacity have contemplated the use of systems of small capacity and the heating of water in a water tank during mild weather and using this stored heat to heat the house during the periods when the refrigeration system lacks sufficient capacity. This system is impractical for tremendous quantities of water are involved. It is much more desirable to provide a system of sufficient capacity and to unload a portion of the system when all of the capacity is not required.

One type of reverse cycle system or heat pump has the evaporator exposed to the atmosphere to extract heat therefrom. This type of system has certain inherent advantages relating to its installation. However, it also presents additional difficulties. In view of the fact that the function of the evaporator is to extract heat from the atmosphere it is evident that when the outside temperature increases the system has its greatest heat extracting capacity. Unfortunately this is just the reverse of what is desired, for the greatest demand for heat exists when the outside temperature is low and at this time with present systems of this type the capacity of the system to obtain heat is lowest. It is an object of this invention to provide means for adjusting the capacity of a reverse cycle system and to provide in this means a recognition of the changes in its capacity.

The volume of air delivered by either system is determined by the requirement for air at the established delivered air temperature under extreme conditions. The temperature of the delivered air in the conventional system increases as the load decreases or outside temperature increases. Since the system operates under what may be termed a partial load for the major portion of the season the delivered air temperature of a conventional system is greater than necessary most of the time and it is axiomatic that as the delivered air temperature increases the efficiency of the system decreases. In contrast to this in a system operating in accordance with my invention the delivered air temperature may be decreased as the load on the system decreases (i. e. outside temperature increases). Throughout the major portion of the season when partial load conditions prevail the temperature of de-

delivered air is therefore less with my invention than in a conventional system and therefore the season average of the efficiency is greater. The volume of air delivered per unit of time by either system is constant for that system throughout the season but this volume may be established at a lower value in a system incorporating my invention for a higher delivered air temperature may be used under extreme load conditions without significantly penalizing the efficiency of the system under the more frequent partial load conditions.

In addition, discussions heretofore made involving heat pumps and reverse cycle systems have considered the advisability of using the system for heating during winter months and cooling during summer months. This produces an additional problem in view of the fact that the system and particularly the compressor of the system will have altogether too much cooling capacity compared to the heating capacity required to handle a given installation. For example, a 5 H. P. compressor might be required to provide the necessary B. t. u. output for heating a particular residence whereas only a 2 H. P. compressor would be required to cool the same residence. It is an additional object of this invention to provide a means for varying the capacity of the system between summer and winter requirements.

It is a further object of this invention to provide a reverse cycle system or heat pump with a compressor unloading means therein and to provide means for utilizing the refrigerant pressure within the system to operate the unloading means.

It is an additional object of the invention to provide a heat pump or reverse cycle system having a variable capacity compressor therein and control means to vary the capacity of the compressor in response to outside temperature and delivered air temperature conditions. If desired, a supplemental control may be associated with the system to initiate the operation of the system in response to a room temperature thermostat.

It is a further object of the invention to improve the electrical load characteristics of a reverse cycle heating system. It is recognized that an electrical power supply company finds a reduced load operating for a relatively long length of time to be more acceptable than a relatively high load imposed for short intervals. Varying the capacity of the compressor rather than varying the time of operation of a compressor of fixed capacity accomplishes this.

These and other objects of my invention will become apparent from the following description taken in conjunction with the accompanying drawings in which:

Fig. 1 is a diagrammatic showing of a heating system for a residence incorporating my invention;

Fig. 2 is an elevation, partly in section of a compressor having an unloader means incorporated therein;

Fig. 3 is an enlarged fragmentary section of a portion of the Fig. 2 compressor unloader means;

Fig. 4 is a vertical sectional view of a control adapted to be incorporated in the reverse cycle system;

Fig. 5 is a pair of charts from which computations will be made to show the relative efficiency of a conventional reverse cycle system and a variable capacity reverse cycle system where these systems each have their evaporator buried in the ground; and

Fig. 6 comprises 3 charts from which computations showing the relative efficiency of a conventional system and a system incorporating my invention will be made where these systems utilize an evaporator coil exposed to the atmosphere.

In Fig. 1 a residence 10 is illustrated as having a room 12 therein which is to be heated by a reverse cycle refrigerating system. A hot air discharge grille 14 and a cold air return grille 16 are illustrated as being connected by a duct 18. A fan 20 is positioned in the duct to induce the circulation of air therein. The condenser 22 of a reverse cycle refrigeration system is also located in the duct 18 so that air circulating therein is heated by passing through the condenser 22. The air from room 12 is thus recirculated and heated by the condenser 22.

The reverse cycle refrigerating system which provides heat to the condenser 22 comprises a compressor 24 having unloading means 26 associated therewith, an expansion valve 28 and an evaporator coil 30. The evaporator coil 30 may either be located in the air outside of the building 10 or be buried in the ground adjacent the building 10. Refrigerant is conveyed from the evaporator 30 to compressor 24 by line 32. The compressed refrigerant is delivered from compressor 24 to condenser 22 by lines 34 and 36 and conveyed from condenser 22 to the expansion valve 28 by a line 38. The unloading means 26 to be described herein receives compressed refrigerant from compressor 24 through lines 34, 40, and 41. The passage of refrigerant to unloading means 26 through lines 40 and 41 is regulated by a control means generally designated by the numeral 42. The control means 42 operates in response to a temperature bulb 44 located in the duct 18 and temperature bulb 46 located outside the building 10 and throttles the supply of refrigerant to unloading means 26 in response to conditions measured by the bulbs 44 and 46. A line 48 having a restriction 45 therein is provided to bleed refrigerant from unloading means 26 to suction line 32.

If desired a supplemental control may be provided to initiate and terminate the operation of the compressor 24 in response to room temperature conditions. Electric energy to operate the compressor 24 is provided by an electrical line 48 and an electrical line 50. The electrical line 50 contains a switch 52 which is opened by a spring 54 and closed by a solenoid 56. The solenoid 56 is wired in series with a source 58 of low voltage electric energy and a room temperature responsive thermostat switch 60. When the room temperature responsive thermostat 60 demands heat the switch (not shown) therein is closed and the electrical circuit between source 58 and solenoid 56 is closed. Energization of solenoid 56 closes switch 52 which completes the electrical circuit to compressor 24. Although means will be described herein for controlling the delivery of heat by the system in response to outside temperature conditions the supplemental room thermostat control is desirable for it is able to compensate for conditions such as whether the day is sunny or cloudy or whether a high wind is blowing. In other words, control 42 determines the capacity of the system during each operating period, but the duration of the operating period is determined by thermostat 60.

Referring to Figs. 2 and 3 the construction of the compressor 24 and the unloading means 26 may be seen in greater detail. The compressor 24 unloading means illustrated herein is described

in greater detail in my application, Serial No. 792,277, filed December 17, 1947, as a continuation in part of application, Serial No. 625,864, filed October 31, 1945, now abandoned. Compressor 24 comprises an electric motor 62 which drives a compressor crankshaft 64 to which are connected a plurality of connecting rods 66 each operating a piston 68 in a cylinder 70. A suction manifold 72 in the compressor is connected to the line 32 by an orifice (not shown). Refrigerant passes into the interior of each of the cylinders 70 through a suction valve 74 and is ejected through a discharge valve 76 into a discharge passage 78 operatively connected to the line 34 by an orifice. Details of the valve and piston construction may be ascertained from the Patent No. 2,137,965, which issued on November 22, 1938, and the Patent No. 2,185,473 which issued on January 2, 1940, to Charles R. Neeson.

The suction manifold 72 is connected through ports 80 with the interior space 82 of the compressor crankcase containing a flexible metallic bellows 84. Bellows 84 is thus subjected to the pressure of expanded refrigerant returned from the evaporator 30. Movement of the bellows 84 which has an end piece 86 welded to a link rod 88 causes reciprocation of the link rod 88 which is connected by rocking levers 90 to a master valve member 92 contained in a master valve 93. The master valve member 92 is provided with a plurality of notches 94 so that a spring pressed ball 96 engaging in the notches permits step by step movement of the master valve member. Each step causes one of a plurality of slots 98 to be connected to or disconnected from a source of oil pressure in an oil pressure tube 100. Each of the slots 98 is connected to a short tube 102 leading to a cylinder 104 (Fig. 2) in which is mounted a spring loaded unloader piston 106 connected to an unloading mechanism including a yoke 108 adapted to ride on a ramp 110 and to be moved axially of piston 68 as the piston 106 moves the yoke 108 longitudinally. The yoke causes axial movement of a collar 112 having unloader pins 114 mounted thereon which when moved axially causes the suction valve 74 to be held open continuously whereby the cylinder is unloaded. The position of the movable valve part 92 therefore controls the number of unloader pistons 106 to which oil pressure is applied and hence controls the number of cylinders in operation. When as disclosed in Fig. 2 all but one of slots 98 are connected to tube 100 through the annular space surrounding a reduced portion of valve member 92 all but one of the individual cylinders will be loaded or operating. When valve member 92 is moved to the left by the length of another notch 94 two cylinders will be unloaded since another one of the unloader cylinders 104 will be disconnected from the source of oil pressure.

Oil pressure is applied to the unloader mechanism through the master valve from a pressure lubrication pump (not shown) details of which may be ascertained from the aforesaid Patent No. 2,185,473. The oil pressure pump operates coextensively with the operation of motor 82 so that no oil pressure will be supplied to the master valve unless the motor is operating and since it takes a short while for the pressure to be built up by the oil pump it is apparent that all cylinders will be unloaded during starting thereby preventing large starting current demand. It is also apparent that after oil pressure is available

a number of cylinders may be unloaded depending upon the position of the link rod 88.

The position of link rod 88 may be controlled by the degree of compression of the flexible metallic bellows 84 which compression is effected by the pressure of the refrigerant in the space 82 connected to the suction side of the refrigerating system through the port 80. The pressure of the gas against bellows 84 operates 5 against a compression spring 116 positioned between the end of the bellows and a disc 118. The disc has wings 120 at opposite sides projecting through a slot in a threaded sleeve 122. The sleeve is secured as by welding to an apertured 10 member 124 to which the bellows 84 is secured. A nut 128 threaded on the sleeve 122 determines the position of the disc 118 and consequently the compression of the spring 116. The link rod 88 has a reduced outer end on which is threaded 15 a nut 128 serving to guide the rod in sleeve 122. A lock nut 130 retains the nut 128 in position. An additional light spring may be provided to react between nut 126 and nut 128. This facilitates an adjustment of the spring pressure opposing compression of bellows 84 since springs 116 and 131 oppose each other. The resultant spring force controls the unloading pressure of the master valve 93 so that the suction pressure of 20 the refrigerating system may be controlled with 25 reasonable limits.

In addition to the use of suction pressure to determine the compressor unloading additional means for unloading the compressor in response to temperature of the heated delivered air and the outside temperature are provided. A housing 132 is secured in fluidtight relationship to apertured member 124. A collar 134 is threaded on housing 132 and a dome 136 is secured as by welding to the collar 134. An orifice 138 is provided in housing 132 and has connected thereto the line 41 adapted to conduct refrigerant to the interior of the housing 132 and dome 136 so that the pressure of this refrigerant may act upon the interior of the bellows 84. Thus on the exterior of the bellows 84 the suction pressure tends to compress the bellows. From the interior of the bellows 84 the spring 116 and the pressure of refrigerant supplied by line 41 are tending to expand the bellows 84. The resultant of these forces acting on the bellows 84 will determine the degree of compression thereof and thereby determine the position of the link rod 88 and the master valve member 92 which in turn determines the number of cylinders of compressor 24 which are loaded. The refrigerant permitted to enter unloading means 26 from line 41 is controlled by a control 42. The line 43 bleeds refrigerant from dome 136 and thereby permits the pressure within dome 136 to decrease when the supply from line 41 is restricted. The line 43 is provided with a restriction and the capacity of this bleed line 43 is less than the capacity of line 41 so that pressure may be built up in dome 136 when the line 41 is not restricted by control 42.

The control 42 is adapted to throttle the supply of refrigerant from line 34 of the compressor 24 through the lines 40 and 41 to the unloading means 26. A control means similar to the control 42 used for a different application is illustrated in my copending application, Serial No. 763,596, filed July 25, 1947. The lines 40 and 41 conducting refrigerant from compressor 24 to compressor unloading means 26 have the control 42 positioned between them. The control 42

serves as a valve governing the passage of refrigerant from line 40 to line 41.

The control 42 is mounted in a housing 166 having openings in which the lines 40 and 41 are received. A dome 170 is secured to a side wall of the housing 168 over an opening 171 therein. A pressure responsive bellows 172 is positioned within the dome 170 and cooperates therewith to form a liquidtight compartment 174. The bulb 46 previously referred to is connected to compartment 174 and the compartment 174 and bulb 46 are filled with an expansible medium such as one of the liquids commonly employed for this purpose. Temperature changes will cause the medium in the bulb 46 to expand and activate the bellows 172. The bulb 46 is positioned outside the building 10 as illustrated in Fig. 1 and exposed to the atmosphere. A rod 176 is adjustably secured to the bellows. An L-shaped lever 178 is pivoted at 180 and has one leg thereof adapted to be engaged by the rod 176. Movement of the rod 176 rotates the lever 178 about the pivot 180 against the spring 181 to be described. The other leg of the lever 178 has a valve element 182 in the form of a pad secured to the end thereof. Valve element 182 is positioned in a predetermined position for each outside temperature by the apparatus described.

A similar mechanism is provided to control the position of a second valve element 184. A dome 186 is associated with the housing 168 and contains a bellows element 188 which cooperates with the dome 186 to provide a liquidtight compartment 190. The compartment 190 is connected to the bulb 44 which was previously referred to and the bellows 188 is activated by expansion and contraction of a medium provided in the compartment 190 and bulb 44. Bulb 44 is positioned in the heated air delivery duct 18 as shown in Fig. 1. A lever 192 carrying valve element 184 is pivoted on the housing 168 at 194. The spring 181 tends to separate levers 178 and 192 while movements of the bellows elements tend to move the levers toward each other. A lever 196 is pivoted on the housing 168 at 198. A plate member 200 is also pivoted at 198. A threaded element 204 is positioned between levers 192 and 196 and in engagement with these levers. The threaded element 204 is threaded upon an adjusting rod 206 carried by the plate member 200. A knob 208 is provided on rod 206 for manual adjustment thereof. A rod 210 is operatively connected to the bellows 188 and adapted to engage the lever 196 in response to contraction and expansion of the bellows 188. Means are thus provided to position the valve element 184 in a predetermined position for each temperature in the duct 18. The valve element 184 is connected by a flexible tube 212 to the line 40. It will thus be seen that the valve element 182 when properly positioned can close the tube 212 so that refrigerant cannot be emitted therefrom. When valve 182 is positioned away from valve element 184 so that refrigerant may escape from line 40 and tube 212 the housing 168 is filled with refrigerant which enters line 41 and is transmitted thereby to unloading means 26. A modulating control is thus provided. The supply of refrigerant to the unloader control means 26 is thus dependent upon both outside temperature conditions and the temperature of the air in the duct 18 which are measured by the bulbs 46 and 44 respectively. Although refrigerant has been described as the medium delivered by pipe 41 to control the unloading of the compressor cylind-

ders it is to be understood that a source of compressed air could be substituted so that the air supply to the unloading means 26 would be modulated by control means 42. A system using an air supply to operate the unloader means is illustrated in my copending application Serial No. 792,277 referred to above.

As previously explained in setting forth the objects of my invention the outside temperature dictates the requirement for heat and when an evaporator exposed to the atmosphere is used the capacity of the system to absorb heat is also a function of the outside temperature. Both of these factors are therefore important in selecting the optimum capacity of the compressor which is accomplished by unloading means 26. In addition, the temperature of air in duct 18 is directly related to the ability of this air to heat the room 12 and therefore the capacity of compressor 24 has been controlled so that its capacity is sufficient at all times to provide a satisfactory temperature of heated air in duct 18.

Changes in the condition of the heat source are automatically compensated for by the apparatus described herein. For example, where an evaporator exposed to the atmosphere accumulates frost or where long continuous operation of a ground coil lowers the temperature of the ground in the vicinity of the coil the ability of a conventional reverse cycle system to deliver heat is impaired. In contrast to this the controls described herein automatically adjust the system to compensate for this change in the condition of the heat source. This change induces a drop in compressor suction pressure which is followed by a drop in compressor discharge pressure and temperature which in turn drops the delivered air temperature which activates bulb 44 which automatically loads the compressor to compensate for this. The compressor loading as described herein is therefore controlled in response to four conditions which include the outside air temperature, the delivered air temperature, the condition of the heat source as explained above, and the room temperature by the thermostat 60.

In Fig. 5 charts have been illustrated which facilitate a comparison of the efficiency of a reverse cycle heating system controlled by an "on-off" thermostat and a system incorporating my invention in which the compressor displacement capacity may be varied. Both of these systems have the evaporator buried in the ground. The chart on the left labelled "conventional system" shows the ground at a temperature of 50° F. as the heat source. Under heavy load conditions a reasonable evaporator temperature would be approximately 20° F. which corresponds to 37 pounds absolute pressure. To produce a 70° room temperature under extremely cold conditions the delivered air temperature would be about 110° F. and this would require a condenser temperature of about 130° F. which corresponds to 194 pounds absolute pressure. The efficiency or power requirements of the system are related to the absolute pressures of the refrigerant in the system because the density of the refrigerant increases as its absolute pressure increases and therefore, a greater weight of refrigerant will be compressed as the density increases. By consulting tables familiar to those skilled in the art it may be seen that .124 H. P. per thousand B. t. u.'s per hour of operation of the heating apparatus would be required for this conventional system.

It is estimated for a typical locality that the average of the heating requirements over the period of a season approximate 40% of the maximum requirements under extreme conditions. By varying the capacity of the system advantage may be taken of this fact. Referring to the chart in Fig. 5 labelled "Variable capacity system" the system has been illustrated as operating at its usual or average load which is only 40 per cent of its potential capacity. The average delivered air temperature is considerably lower and the average condenser temperature and pressure are lower while the average evaporator temperature is higher than in the "conventional system" chart. Note that the disadvantage in the conventional system was that its time of operation could be controlled but its capacity was always that required for extreme conditions. Reference to the tables previously referred to disclosed that the average horsepower requirement for the season for the variable capacity system is .054 H. P. per thousand B. t. u.'s per hour of operation. Therefore, over the period of a season the variable capacity system requires only about forty-three per cent of the power or electrical energy that the conventional system requires.

In Fig. 6 a similar set of charts have been illustrated for systems using evaporators exposed to the atmosphere. In view of the fact that changes in outside temperature affect the efficiency of the conventional system of this type, this system has been shown with an outside temperature of 0° F. and an outside temperature of 40° F. The outside temperature of 40° F. has been used as illustrative of the average of temperature conditions which might be obtained in certain localities over the period of a season while the 0° F. has been used as illustrative of extreme conditions for which the apparatus must be designed. By computations similar to that explained with reference to Fig. 5 it is seen that the horsepower requirements vary between .18 H. P. per thousand B. t. u.'s per hour for operation at 0° F. and .218 H. P. per thousand B. t. u.'s per hour for operation at 40° F. In the latter case the absolute pressures are greater and the capacity of the system cannot be varied and therefore the efficiency of the system is lower. By contrast to this the "Variable capacity system" operating at its seasonal average of 40% of its capacity or 40° F. uses .057 H. P. per thousand B. t. u.'s per hour. The savings in energy consumption produced by varying the capacity of the system are thus of major proportions and constitute an unanticipated result obtained by the modification of the reverse cycle system as described herein.

The charts of Figs. 5 and 6 illustrate the fact that with my improved control the temperature difference between the refrigerant in the evaporator and the heat source and the temperature difference between the refrigerant in the condenser and the substance to be heated are simultaneously controlled so that each of these temperature differences are maintained at the minimum value compatible with the requirement for heat.

I claim:

1. In a reverse cycle refrigeration system having an evaporator located in heat transfer relation with a source of heat, a condenser located in heat transfer relation with a substance to be heated and a compressor, unloader means to vary the capacity of said compressor and control ap-

paratus responsive to conditions indicating the available heat in said source and the demand for heat by said substance to control said unloader means and thereby adjust the capacity of said system so that it operates at its optimum efficiency for said conditions.

2. In a reverse cycle refrigeration system having an evaporator located in heat transfer relation with a source of heat, a condenser located in heat transfer relation with a substance to be heated and a compressor, unloader means to vary the capacity of said compressor and control apparatus responsive to the temperature of said source and the temperature of said substance to control said unloader means to determine the number of operating cylinders in said compressor to thereby adjust the capacity of said system so that it operates at its optimum efficiency.

3. In a reverse cycle refrigeration system adapted to heat a space in a building by extracting heat from a natural source outside of said building, a compressor, a cylinder unloading mechanism associated with said compressor and adapted to vary the capacity thereof by determining the number of loaded cylinders in said compressor and control mechanism responsive to temperature changes outside of said building to control the operation of said unloading mechanism whereby the capacity of said compressor is at all times a function of the temperature outside of said building.

4. In a building having a space to be heated and a duct for heated air to heat said space, a reverse cycle refrigeration system to heat air in said duct comprising a condenser located in heat transfer relationship with said air, an evaporator adapted to assimilate heat from a source outside of said building, a refrigerant compressor, a cylinder unloading mechanism associated with said compressor and adapted to reduce the capacity of said compressor by unloading individual cylinders thereof and control means responsive to the temperature outside of said building to control the operation of said unloading mechanism so that the capacity of said compressor is at all times a function of the temperature outside of said building.

5. In a building having a space to be heated and a duct for heated air to heat said space, a reverse cycle refrigeration system to heat air in said duct comprising a condenser located in heat transfer relationship with said air, an evaporator adapted to assimilate heat from a source outside of said building, a refrigerant compressor, a cylinder unloading mechanism associated with said compressor and adapted to reduce the capacity of said compressor thereof, control means responsive to the temperature outside of said building and to the temperature of heated air in said duct to control the operation of said unloading mechanism so that the capacity of said compressor is at all times a function of said temperatures.

6. In a refrigeration system, means forming a circuit for refrigerant in said system, a multi-cylinder compressor interposed in said circuit, unloader mechanism associated with said compressor and adapted to unload individual cylinders of said compressor and control means for said unloader mechanism including a path for said refrigerant forming a portion of said circuit, said control means being adapted to regulate the flow of refrigerant in said path and to deliver said regulated flow of refrigerant to said unloader mechanism to control the latter.

7. In a reverse cycle refrigeration system hav-

ing an evaporator located in heat transfer relation with a source of heat, a condenser located in heat transfer relation with a substance to be heated, a compressor and means forming a circuit for refrigerant through said evaporator, said compressor and said condenser, unloader means interposed in said circuit to vary the capacity of said compressor in response to the pressure of refrigerant supplied to said unloader means and control means adapted to throttle the supply of refrigerant to said unloader means in response to outside atmosphere temperature and in response to temperature of the substance to be heated.

8. In a reverse cycle refrigeration system having an evaporator located in heat transfer relation with a source of heat, a condenser located in heat transfer relation with a substance to be heated and a compressor, unloader means to vary the compression ratio of said compressor and control apparatus responsive to outside temperature and to the demand for heat to control said unloader means and thereby adjust the compression ratio of said compressor.

9. In a reverse cycle refrigeration system adapted to heat a space in a building by extracting heat from the outside atmosphere, an evaporator exposed to said atmosphere, a condenser located in heat transfer relation with respect to said space, a compressor, unloader means to vary the capacity of said compressor and control apparatus associated with said unloader means and adapted to operate said unloader means in response to changes in the capacity of said system to absorb heat from the atmosphere.

10. In a reverse cycle refrigeration system having an evaporator located in heat transfer relation with a source of heat, a condenser located in heat transfer relation with a substance to be heated, a compressor and means forming a circuit for refrigerant through said evaporator, condenser and compressor, unloader means to vary the capacity of said compressor and control apparatus adapted to maintain the mean temperature differential between said refrigerant and said source and said refrigerant and said substance at a predetermined minimum.

11. In a reverse cycle refrigeration system adapted to heat a space and having an evaporator located in heat transfer relation with a source of heat, a condenser located in heat transfer relation with a substance to be heated and a compressor, unloader means to vary the capacity of said compressor, control apparatus responsive to conditions indicating the available heat in said source and the demand for heat by said substance to control said unloader means and thereby adjust the capacity of said system and supplemental space temperature responsive control means adapted to initiate and terminate operation of said compressor in response to space temperature conditions whereby the capacity of said system during each operating period is established by said control apparatus and the duration and frequency of the operating periods are determined by said supplemental control means.

12. In a reverse cycle refrigeration system adapted to heat a space and having an evaporator located in heat transfer relation with a source of heat, a condenser located in heat transfer relation with a substance to be heated and a compressor, space temperature responsive control means to initiate and terminate operation of said compressor and control apparatus responsive to the temperature of air delivered to said space

5 to control the capacity of said system during each operating period of said compressor so that the heat supplied by delivered air during each operating period will equal or exceed the demands of the space.

13. In a reverse cycle refrigeration system adapted to heat a space and having an evaporator located in heat transfer relation with a source of heat, a condenser located in heat transfer relation with a substance to be heated and a compressor, space temperature responsive control means to initiate and terminate operation of said compressor and control apparatus responsive to the outside temperature to control the capacity of said system during each operating period of said compressor so that the heat supplied by said system to said space during each operating period will equal or exceed the demands of the space for the existing outside temperature conditions.

14. In a reverse cycle refrigeration system adapted to heat a space and having an evaporator located in heat transfer relation with a source of heat, a condenser located in heat transfer relation with a substance to be heated and a compressor, unloader means to vary the capacity of said compressor and control apparatus adapted to control said unloader mechanism so that the heat discharged by said system to said space is substantially constant when the ability of said evaporator to obtain heat decreases, said control apparatus being adapted to cause said unloader means to increase the loading of said compressor to maintain the discharge of heat by said system at a constant value during a uniform weather condition.

15. In a space heating apparatus utilizing a reverse cycle refrigeration system to obtain heat outside said space and to deliver said heat to said space a refrigerant compressor, cylinder unloading mechanism associated with said compressor and control apparatus to control said unloading mechanism, said control apparatus including means to control said unloading mechanism in response to changes in the temperature of air delivered to said space to compensate for changes in the ability of said system to absorb heat from the outside, means to control said unloading mechanism in response to changes in temperature outside of said space, and supplemental space temperature responsive control means to initiate and terminate the operation of said compressor in response to changes in the temperature of said space.

16. In a reverse cycle refrigeration system adapted to heat a space in a building by extracting heat from a natural source outside of said building and heating air from said space, a compressor, a cylinder unloading mechanism associated with said compressor and adapted to vary the capacity thereof by determining the number of loaded cylinders in said compressor and control mechanism responsive to the temperature of said heated air to control the operation of said unloading mechanism.

17. In a building having a space to be heated and a duct for heated air to heat said space, a reverse cycle refrigeration system to heat air in said duct comprising a condenser located in heat transfer relationship with said air, an evaporator adapted to assimilate heat from a source outside of said building, a refrigerant compressor, a cylinder unloading mechanism associated with said compressor and adapted to reduce the capacity of said compressor by unloading individual cylinders thereof, and control means responsive to the tem-

perature of air in said duct to control the operations of said unloading mechanism so that the capacity of said compressor is at all times a function of the temperature of air in said duct whereby the effect of outside conditions on said system is automatically compensated for by adjusting the capacity of the system to produce an optimum delivered air temperature.

18. In a reverse cycle refrigeration system including an evaporator for refrigerant located in heat transfer relation with a source of heat and adapted to receive heat by virtue of a first temperature differential between said refrigerant and said source, a condenser for refrigerant located in heat transfer relationship with a substance to be heated and adapted to deliver heat to said substance by virtue of a second temperature differential between said refrigerant and said substance, a compressor to pump heat and refrigerant from said evaporator to said condenser, cylinder unloading mechanism associated with said compressor and control mechanism to control said unloading mechanism so that the said first and second temperature differentials are maintained at the minimum values capable of delivering the required heat to said substance.

19. In a building having a space to be heated and a duct for heated air to heat said space, a reverse cycle refrigeration system to heat air in said duct comprising a condenser located in heat

transfer relationship with said air, an evaporator adapted to assimilate heat from a source outside of said building, a refrigerant compressor, a cylinder unloading mechanism associated with said compressor and adapted to reduce the capacity of said compressor by unloading individual cylinders thereof, and control means adapted to control the operation of said unloader mechanism so that the differential between the temperature of the heated air in said duct and the desired space temperature is maintained at a minimum value sufficient to heat said space.
